HEEL TRIMMING MACHINE

Edward B. Carter, Lexington, Mass.

Application October 17, 1930, Serial No. 489,370

44 Claims. (Cl. 164—63)

My present invention relates to trimming machines and more particularly to machines for trimming fins from molded rubber heels.

In the present practice of manufacturing rubber heels, a biscuit of suitable rubber compound is placed in a mold, and then subjected to heat and pressure. It is customary to have a surplus of the material required for the completed heel, in order to insure filling of the mold, as well as 10 to eliminate air pockets or other faults in the completed heel. This excess or surplus material, as a result of the pressure to which the biscuit is subjected, is extruded from the mold along the top and bottom edges of the heel, forming 15 what is known in the heel industry as fins. Before the heels are in a marketable condition these fins must be removed and the removal must be performed in such manner as to not leave any 20 unsightly edges, protuberances, or other flaws in the completed heel.

Many machines have been devised for performing this fin trimming operation, but all 25 these prior machines have operated upon but one edge of the heel at a time, requiring a double operation in order to effect the removal of the fins from the top and bottom edges of the heel. In most of these prior machines, also, the presenting of the heel edges to the cutting elements 30 has been done by hand, this being a dangerous operation, because of the possibility of injury to the operator by reason of the proximity of the hands of the operator to the cutting elements.

An important object of the present invention is 35 the provision of a machine which will effect a trimming of the fins from the top and bottom edges of a heel simultaneously, thus performing in one operation what has heretofore required two operations.

Another object of the present invention is the 40 provision of a heel trimming machine which will have a maximum factor of safety, eliminating the likelihood of injury which has been present in most prior machines.

Commercial rubber heels have a peculiar contour, in that on the side thereof there is substantially no longitudinally straight line, and substantially no true arc of a circle. In order to 45 effect a neat trimming of the fins from the heel edges, it is essential that the edges of the heel 50 to be trimmed shall be presented to the cutting elements in a continuously smooth path of movement and under a constant pressure. This I accomplish in my present machine.

In my present machine I provide a pivoted 55 carriage, adapted to be engaged by a heel in its

passage through the machine, means being provided to effect a feeding of the heel through said machine. Until said carriage is engaged by said heel, the feeding means feeds the heel forwardly, presenting the top and bottom edges to their respective cutting elements. Said carriage is provided with an arcuate plate adapted to be engaged by the heel breast, and simultaneously with the engagement of said arcuate plate by said heel breast, cam operated spring-pressed gripping elements are brought into engagement with the heel, centering said heel in a fixed position in its carriage. 5

Meanwhile the feeding means is exerting a continuous feeding action upon the heel. The heel, 15 however, is now firmly held in its carriage, and is prevented from further movement through the machine by said carriage. The carriage, however, is pivotally mounted, and the action of the feeding means on the heel will cause said heel 20 to rotate said carriage about its pivot whereby the heel will be rotated about a desired center.

This rotation of the carriage about its pivot will continue until the curved portion of the heel 25 has received its trimming operation, whereupon the heel will be released from its carriage and the gripping elements, and the feeding means will again effect a travel of the heel through the machine, completing the trimming of the side 30 of said heel opposite the side first operated upon. When trimming of the heel is completed, discharging means is provided to eject the heel from the machine, and during such ejection the heel will engage means associated with the heel carriage 35 to automatically return said heel carriage to its initial position in readiness for the reception of a subsequent heel. It will thus be seen that operation of the heel carriage is effected by the heel itself, as is also the return of said carriage to normal position. 40

Means is associated with the machine, as well as with the heel carriage, to present the proper portion of the heel to be trimmed to the cutting elements, and means is also provided to spread the fins from the heel in order to insure their severance from the heel by the cutting elements. 45

As the heel curve of these rubber heels rarely has the arc of a true circle, the heel carriage is resiliently mounted, in order that the shape of the heel may vary the relation of said carriage 50 to the cutting elements, and thus continuously compensate for any unevenness in heel contours.

In my present machine the cutting elements 55 comprise two pairs of cutters, each consisting of a top and bottom cutter, and each pair of cut-

ters being adapted to operate upon one edge of a heel presented thereto; and another feature of my invention resides in the provision of resilient means to retain the top cutting elements against the lower or bottom cutters.

Another object of the invention resides in the particular construction of the heel feeding means, which comprises a pair of knurled rollers, one associated with each of the top cutters. One of these rollers is straight, and is adapted to engage the flat surface of the heel, adjacent to the edge thereof, the other roller being slightly convexed to engage the concave side of the heel, and thus effect a firm grasp of these feeding rollers on the heel and assuring a positive feeding of the heel through the machine. The engagement of the convex feeding roller with the concave side of the heel will also effect a downward pressure of said heel against the cutters, thus still further insuring proper presentation of the finned edges of the heel to the cooperating cutters.

Another object of my invention resides in the provision of means to remove the severed fins from the cutters.

A still further object of the invention resides in the provision of means to discharge the severed fins from the machine.

Another object of the invention resides in the provision of means to adjust the bottom cutters horizontally with relation to the top cutters to accommodate varying sizes of heels, as heels of different thicknesses will require different adjustment of the bottom cutters relative to their co-operating top cutters.

Another object of the invention resides in the fact that the entire heel carriage is easily removable and replaceable.

Another feature of the invention resides in the provision of manually operable means to adjust said carriage relative to the cutters to accommodate varying sizes of heels, as the centering point will vary with varying sizes of heels. This manual adjustment is in addition to the automatic adjustment heretofore mentioned for compensating for unevennesses in heel contours.

A further feature of the invention resides in the provision of means to permit automatic adjustment of the top cutters relative to each other to compensate for varying thicknesses of heels, or for varying points of thickness in a single heel.

A still further feature of my present machine is the elimination of the use of oil or water to reduce frictional heat, which has been necessary in many prior machines.

Other objects and features of the invention reside in the particular construction, arrangement and relation of parts of my machine.

While I have illustrated and described the machine of the present application as particularly adaptable to heel trimming, it will be appreciated that said machine may operate, with equal facility, upon other rubber articles, wherein it is desired to remove a fin or fins therefrom.

The above and other features and objects of my invention, combinations of parts, details of construction, and advantages, will be hereinafter more fully pointed out, described and claimed.

Referring to the drawings, illustrating a preferred embodiment of my present invention,

Fig. 1 is a side elevation, partly in section, of my novel machine;

Fig. 2 is a plan sectional view on the line 2—2 of Fig. 1;

Fig. 3 is a front elevation, partly in section;

Fig. 5 is a fragmentary plan sectional view on the line 5—5 of Fig. 4;

Fig. 6 is a fragmentary vertical sectional view on the line 6—6 of Fig. 5;

Fig. 7 is a fragmentary view illustrating the beginning of the cutting operation;

Fig. 8 is a view during the trimming operation;

Fig. 9 is a view as the heel approaches completion of its trimming operation;

Fig. 10 is a vertical sectional view on the line 10—10 of Fig. 8;

Fig. 11 is a perspective view of the heel carriage;

Fig. 12 is a perspective view, on an enlarged scale, illustrating the manual and automatic adjusting means for the heel carriage;

Fig. 13 is a plan sectional view illustrating the means to feed the severed fins from the cutting knives, and a modified means of removing the severed fins from the bottom cutter;

Fig. 14 is a fragmentary top plan view illustrating the driving gears.

Referring now to the drawings for a particular description of the invention, its construction, assembly and operation, 15 designates a base or supporting plate on which is mounted a motor 16 driving, through shaft 17, coupling 18, shaft 19 and speed reducing unit 20, a shaft 21. Fixed on said shaft 21 is a beveled gear 22 meshing with a beveled gear 23 fixed to a short shaft 24 which is connected to a vertical driving shaft 25 through the medium of a universal joint 26. The gear 23 and shaft 24 are supported in a bracket 27 secured to the standard 28 by bolts 29.

The shaft 25 extends vertically and has bearings in the journal portions 71 of a plate or wall 72, said plate or wall 72 being pivotally mounted on a horizontal shaft 73, which shaft is supported in the vertical wall 74 rising from the base 15, the two walls 72 and 74 having alternating cut-out portions to permit pivoting of the plate 72 on the shaft 73. The plate 72 is normally held in vertical position by means of bolts 75 threaded into the standards 28 and 76, knurled handles 77 being provided on each of the bolts 75. The shaft 25 carries on its upper end a large driving gear 30. The gear 30 in turn meshes with a gear 31 fixed on a vertical shaft 32, and also fixed on the shaft 32, but below the gear 31, is a gear 33, which is in mesh with the gear 34 fixed on the vertical shaft 35. The gear 33 in turn meshes with a gear 36 pinned to a vertical shaft 37, said shaft 37 being supported at its upper end in an arm 38 as is also the shaft 32. The gear 33 also meshes with an idler gear 39 pinned to a short vertical shaft 40 which is also secured in the arm 38, and pinned to the lower end of the shaft 40 is a gear 41 meshing with a gear 42 on a shaft 43. The gear 34 meshes with a gear 44 on a shaft 45, the upper end of the shaft 45 being supported in an arm 46. The gear 34 in turn meshes with an idler gear 47 on a shaft 48, a gear 49 being pinned to the shaft 48 below the arm 46, and the gear 49 in turn meshes with and rotates a gear 50, fixed to the shaft 51.

The shaft 21 extends forwardly through a boss 52 and has splined thereto and slidably mounted thereon a beveled gear 53 which meshes with a beveled gear 54 on a shaft 55, said shaft being journaled in a bracket 56 fixed to a plate 57 by bolts 58.

The lower end of the shaft 55 has a bearing in a boss 59 on the plate 57, the shaft 55 depending on the line 70

Fig. 3 is a front elevation, partly in section;

ing through said plate and having fixed to its lower end a large gear 60, said gear meshing with and driving a gear of similar size 61 pinned to a shaft 62, which is supported in a vertical boss 62a. The shafts 55 and 62 are parallel, as are also the shafts 32 and 35. Fixed to the upper end of the shaft 55 is a member 63 having a conical upper surface, and provided with a shoulder 64 to which an annular disc 65 is affixed by bolts 10 66, a circular cutting or shearing member 67 being fixed to the annular disc 65. To the upper end of the shaft 62 is affixed a member 68 having a conical upper surface and to which an annular disc 69 carrying a circular shearing or cutting member 70 is affixed in a manner similar to the disc 65.

The cutting discs 67 and 70 are referred to herein as the lower or bottom cutting members, and are rotated by means of the gears 60 and 61 in 20 opposite directions.

To the bottom of the shaft 32 is affixed a circular cutter 78, and affixed to the bottom of the shaft 35 is a circular cutter 79, each of the shafts 32 and 35 being provided with a collar 80 and an 25 anti-friction bearing 81, a coiled spring 82 being positioned between the collar 80 and bearing 81, the bearing 81 facilitating rotation of the spring 82. The bearings 81 are located under the arms or brackets 38 and 46, and the coiled springs 82, 30 therefore, will effect a constant downward pressure on the shafts 32 and 35 and hence on the cutters 78 and 79, insuring that said cutters will be maintained in engagement with their respective cooperating bottom cutters 67 and 70. It will 35 thus be appreciated that as the gears 60 and 61 are rotating the bottom cutters 67 and 70, the gears 33 and 34 are simultaneously rotating the top cutters 78 and 79 in the same direction of rotation as their respective bottom cutters 67 and 70.

40 Fixed to the forward portion of the plate 57 is a vertical rod 83 having a lateral projection 84 extending inwardly toward the machine, and fixed to said lateral projection 84 is a vertical arm 85 carrying an arcuate chute 86 in which 45 are mounted freely rotatable rollers 87. The chute 86 has a pair of flaring sides 88 each provided with a recess 89 alined with the tops of the bottom cutters 67 and 70, and in the recesses 89 50 is placed suitable oil packing 90 to lubricate the cutting edges of the cutters 67 and 70. From an inspection of Fig. 2 it will be seen that the chute 86 extends downwardly and inwardly and covers the cutting edges of the cutters 67 and 70 substantially up to the cutting point, thus eliminating any 55 possibility of an operator having his hands or fingers caught between the cutters 67 and 70 as they approach their point of substantial contact.

The plate 57 is movable inwardly and outwardly by means of an adjusting bolt 91 threaded into 60 a depending boss 92 on the under surface of the plate 57. The plate 57 will be guided in such forward or backward movement in a track 93 formed in the base 15 and said plate 57 is held in fixed relation to said base 15 by plates 94 having beveled edges 95 engaging the beveled edges 96 of plates 97 secured to the base 15 by screws 98, the plates 94 being fixed to the plate 57 by screws 99.

70 It will thus be seen that operation of the adjusting bolt 91 to move the plate 57 forwardly or backwardly will adjust the bottom cutters 67 and 70 relative to the top cutters 78 and 79, increasing or decreasing the space between said cutters 67 and 70 at the cutting point, to accommodate varying sizes of heels to be operated upon.

75 Such movement of the plate 57 will not inter-

fere with the driving of the gears 60 and 61, as I provide a yoke 102 fixed to the boss 59 by screws 103, this yoke spanning the shaft 21 behind the beveled gear 53, which is splined to said shaft but 5 slideable thereon as previously stated. Forward movement of the plate 57, or to the left, as viewed in Fig. 1, will, therefore, cause the yoke 102 to move the beveled gear 53 along the shaft 21, maintaining meshing engagement of the gear 53 with the beveled gear 54.

10 Associated with the cutter 78 and fixed to the shaft 32 for rotation therewith is a knurled feeding roll 100, and associated with the cutter 79 and fixed to the shaft 35 for rotation therewith is a knurled feeding roll 101. The side of the 15 feeding roll 101 is straight, while the knurled surface of the feeding roll 100 is concave, as will be clearly apparent from a glance at the drawings. The direction of the knurling on the rollers 100 and 101 is such that this knurling will tend to 20 force the heel downwardly against the tops of the bottom cutters 67 and 70, in addition to the depressing action effected by the concave roller 100.

25 Fixed to the wall 74 by screws 104 is a bracket 105 having a groove 106 therein on its upper surface in which rides a tongue 107 of a member 108 having a slot 109 therein. A bolt 110 extends through the slot 109 and is threaded into the bracket 105, loosening of said bolt 110 permitting movement of said member 108 along the bracket 30 105. Carried by a pin 111 at the upper end of said member 108 is a pair of rollers 112. By means of the adjustment just described the rollers 112 are adjustable relative to the cutting point, the height of said rollers 112, however, 35 being always in the same plane.

When a heel is to be operated upon, the motor 16 is started, thus rotating the respective top and bottom cooperating cutters. The heel is placed on the chute 86 and fed into the machine 40 breast first, as clearly shown in Figs. 7, 8, and 9. Sliding down the rollers 87 on the chute 86, the heel, here designated as 113, will be engaged by the feeding rollers 100 and 101, the straight roller 101 engaging the flat surface of the heel 113 and 45 the concave roller 100 engaging the concave side of the heel, as clearly illustrated in Fig. 10, thus effecting a feeding of the heel toward the rear of the machine, the heel at this point resting on the tops of the cutters 67 and 70 and being held 50 thereagainst by the roller 100.

The fins which are to be removed are designated as 114, there usually being one of these fins at the top and bottom edge of the heel. As the heel approaches the cutting point, means is 55 provided to force the fins 114 outwardly to better insure their presentation to the cutters at the cutting point. This means may be a blower pipe 115, or other desirable mechanism may be utilized.

60 As the heel is moved toward the rear of the machine by the rollers 100 and 101, the forward edge of the heel will engage the rolls 112 and will be tilted upwardly, continued feeding of the heel finally bringing said heel into engagement with 65 the heel carriage.

70 This heel carriage comprises an arcuate plate 116, adapted to be engaged by the breast of the heel 113, said plate 116 being provided with guiding and alining lips 117 at its top and bottom portions. The plate 116 is fixed to a substantially U-shaped frame 118 having a pair of arms 119, a screw 120 being utilized to affix the plate 116 to said frame 118. A pivot pin 121 is fixed 75 to each arm 119, these pivot pins having bear-

ings in blocks 122 fixed to shelves 123 projecting from the wall 72.

While I have illustrated in Fig. 12 a member 124 separable from the shelf 123 to permit removal 5 of the shaft 35, I am designating the shelf 123 and member 124 as a single member, viz., the shelf.

Screws 125 unite the blocks 122 to the shelves, 10 said blocks being provided with slots 126 by means of which the blocks 122 may be adjusted vertically on the screws 125.

A plunger 127 carries at its lower end a bearing member 128 adapted to bear against the pivot pin 121, this structure being identical on each side 15 of the heel carriage. A spring 129 normally forces the bearing member 128 downwardly on its pivot pin 121, the plunger 127 projecting upwardly through the top of the block 122, and having a handle member 130 on said projecting 20 end. On the block 122 is provided a small shelf 131. Thus, the bearing member 128 may be raised by the handle 130, and on reaching the level of the shelf 131, said bearing member may be turned to rest on said shelf, whereupon the entire 25 heel carriage may be raised out of the blocks 122 and withdrawn from the front of the machine, for removal, repair, or any other reason.

On each block 122, and preferably integral therewith, is a cam 132, the purpose of which will 30 be hereinafter more fully designated.

Pivotedly mounted on each arm 119 is a channel member 133, each of these channel members carrying a plunger 134, said plungers being normally housed in the arms 119 by coiled springs 135 35 which force the channel members 133 outwardly from the arms 119.

Pivotedly mounted on a pin 136 carried in the plate 116 is an L-shaped arm 137, having a yoked end 138 in which a roller 139 is freely 40 rotatable. A coiled spring 140 bears against the end 141 of the arm 137 normally forcing the roller 139 upwardly when said carriage is in normal position, the upward movement of said roller being limited by a stop screw 142 which is adjustable to desired position. Fixed to the rear of the plate 116 is a stop 143 adapted to engage a link 144 when the device is in the position illustrated in Fig. 7 to limit movement of the carriage in a counterclockwise direction as viewed 45 in said figure. The link 144 is at one end fixed to the frame 118 by a screw 145, and the other end of the link 144 is pivotally connected at 146 to the arm 147 of a lever 148 which is slightly arcuate in shape, and which lever is pivoted at 149 50 to the web 150 of the plate 72.

Each of the blocks 122 is provided with a guiding lip 151, the two lips 151 forming a throat into which the heel is fed. As the feeding of the heel 113 is continued, the breast 152 of said 60 heel will engage the face of the plate 116. The heel carriage being fixed against rearward movement, continued feeding of the heel by the rollers 100 and 101 will effect a rotative action of the carriage on its pivot pins 121, as clearly illustrated in Figs. 8 and 9. As said carriage is rotated about its pivot points, the channel members 133 will come into engagement with the cams 132, and riding on these cams will force said channel members 133 toward the arms 119. This cam action 65 will force the plungers 134 inwardly, the relation between the plate 116 and plungers 134 being such that one of the plungers 134 will enter the nail hole 153, which is the lower nail hole at the heel curve portion, while the other plunger 134 70 will be forced into the heel on the concave side 75 thereof, these two plungers 134 being, of course, in alinement.

The heel is thus now rigidly held in its carriage between the arcuate face of the plate 116 and the plungers 134. The heel is thus now rotating about a center, in order to trim the fins 114 from the heel curve portion. As these heel curve portions of the heels rarely represent the arc of a true circle, it becomes essential to compensate for unevennesses of contour in the heel being 10 operated upon. This is accomplished by means of the spring-pressed bearing members 128, which permit a vertical movement of the pivot pins 121 in order that the edge of the heel may always be held on the upper edges of the cutters 67 and 70 15 under the same tension. As the rotative movement of the carriage is continued, the channel members 133 will ride beyond or off the cams 132, whereupon the springs 135 will release the plungers 134 from the heel, permitting the rollers 100 20 and 101 to again feed the heel toward the rear of the machine. As this rearward movement of the heel is continued, the heel will again come in contact with the rollers 112, and will be tilted as illustrated in dotted lines in Fig. 9, the rollers 112 25 forcing the rear end of the heel upwardly and the spring-pressed roller 139 forcing the front end of the heel downwardly, thus insuring proper presentation of the finned edges of the heel to the cooperating cutters. 30

When the heel has reached the position illustrated in Fig. 9, continued feeding thereof toward the rear of the machine by the rollers 100 and 101 will free the heel from its carriage, and when the heel has passed beyond the feeding action of the rollers 100 and 101, it will be in a tilted position, beyond the point of inclination illustrated in dotted lines in Fig. 9, whereupon said heel will drop between and be engaged by the discharging rollers 154, which are rotated by the shafts 43 and 40 51, said shafts in turn being rotated by the gears 42 and 50. 35

The direction of rotation of these discharging rollers 154 is toward the rear of the machine, and as the rollers move the heel in this discharging 45 direction, said heel will engage the lever 148, pivoting said lever on its pivot 149 and automatically returning the heel carriage to its normal position in readiness to receive a subsequent heel, whereupon the operation just described will be 50 repeated. It will thus be seen that the heel itself is the means which actuates the heel carriage, as well as the means which returns said carriage to normal or initial position. 55

The rotation of the heel carriage toward the front of the machine is limited by engagement of the stop member 143 with the right-hand lip 151, viewed from the front of the machine. Thus the stop 143 serves as means to limit the rotative movement of the heel carriage both toward the back and toward the front of the machine. 60

As the heels fed through the machine frequently differ in thickness, and also as an individual heel may have different points of thickness, it is desirable to provide means whereby the feeding rollers 100 and 101 may be laterally adjustable to compensate for such differences in thickness. I accomplish this desirable result by providing a flared opening 155 in the arm or shelf 65 46 through which the shaft 35 passes. Thus, should a point of greater thickness be encountered in a heel being fed through the machine, the shaft 35 and roller 101 will be permitted to rock in the flared aperture 155, this rocking action being against the tension of a spring 156 which 70 75

normally forces a plunger 157 against the shaft 35, normally tending to keep the rollers 100 and 101 at their point of closest relation.

The spring 156 is confined in its recess 158 by 5 a threaded plug 159, said recess being formed in the shelf 123, said shelf 123 being provided with an elongated aperture 160 through which the shaft 35 passes. It will be understood and appreciated that the same feature of adjustment 10 may be applied to the shaft 32 if desired, or that manual adjustments to vary the space between the rollers 100 and 101 may be provided if desired.

It will also be appreciated that as the heel 113 is being fed toward the cutting point, the 15 top edges of the cutters 67 and 70 will deflect the fins outwardly from the edges of the heel, preparatory to their severance, the blower or other fin dividing or separating means being an additional assurance to properly position said fins 20 for presentation to the cooperating cutters.

The feature of removability of the heel carriage also enables easy replacement of carriages for different sizes of heels, the pivot points of 25 said carriage being always the same, although the location of the plungers 134 relative to said pivot points will vary in carriages for different sized heels.

During the trimming operation, it is desirable 30 to provide means to remove the severed fins from the cutters, in order that said cutters may not become cluttered or entangled with the severed fins. I accomplish this desirable result by providing, in each cup-shaped lower cutter, and at the bottom of each shaft 37 and 45, a gear 161 35 rotatable with said shafts. Since the construction of this feature in each lower cutter is the same, description of one will suffice for both. A link 162 extends from the shaft 37 and carries on its outer end a pin 163, mounted on which pin 40 is a gear 164 in mesh with the gear 161 and rotated thereby, and also carried by the pin 163 is a saw-toothed disc 165, the periphery of which is located in close proximity to the inner periphery of the lower cutter, and closely adjacent to the 45 cutting point. Thus as the fins 114 are severed from the heels 113, they will be grasped by the saws 165 and positively removed from the top cutters and the cutting point. The conical shape of the upper surface of the members 63 and 68 50 will insure that the severed fins will be fed to the outer edge of the lower cutters, whereupon any desirable means may be utilized to discharge the severed fins from the bottom cutters.

This last mentioned means may comprise a 55 simple inclined chute 166, up which the severed fins will be forced by the rotative action of the cutters. However, in order to facilitate and insure the discharge of the severed fins, I provide a shaft 167 carrying a plurality of vanes or paddles 60 168 aligned with the chute 166. The shaft 167 has bearings in a bracket 169 fixed to the standard 28 by screws 170, and in a bracket 171 mounted on the reduced end 172 of the shaft 55. The reduced end 172 of the shaft 55 carries a beveled 65 gear 173 which meshes with and rotates a beveled gear 174 fixed to the shaft 167. Thus, as the shaft 55 rotates the cutter 67, it will also rotate the gear 173, resulting in a rotation of the shaft 167 and operation of the paddles 168 to impel the 70 severed fins up the chute 166 and out of the bottom cutters.

In Fig. 13 I have illustrated a modified type of means to discharge the severed fins from the bottom cutters, comprising a suction tube 175, operated from any suitable source of power to

create a suction to draw the severed fins through the tube 175 and outwardly away from the bottom cutters and the machine.

It will thus be appreciated by those skilled in this art that I have devised a machine capable of trimming the fins from both edges of a heel simultaneously, and which machine is capable of operation upon heels in rapid succession, trimming the same in an efficient manner and with a maximum factor of safety to the operators. 10

By having the wall 72 removably attached to the standards 28 and 76, by means of the screws 75, these screws may be released, through the medium of the knurled handles or knobs 77, and the entire head of the machine, including the top cutters, heel carriage, and associated parts, may be rocked backwardly on the shaft 73, permitting access to the said head, for the purpose of removing and replacing the top cutters, or other parts which would be inaccessible with the machine in normal position. This feature greatly facilitates repairs and replacements to the parts carried by the head of the machine. When such repairs or replacements have been made, the head is swung upwardly and the screws 75 again 20 threaded into the standards 28 and 76 and the machine is again ready for operation.

I believe that the machine illustrated and described in this application is novel, and have, therefore, claimed said machine broadly herein. 30

While I have necessarily described my present invention somewhat in detail, it will be appreciated that I may vary the size, shape, and arrangement of parts, within reasonably wide limits without departing from the spirit of the 35 invention.

My invention is further described and defined in the form of claims as follows:

1. In a machine of the kind described, flash trimming means, means to rotate a heel about 40 a predetermined center with its edge in constant trimming relation with said trimming means during the entire trimming operation, means to feed said heel to said rotating means, and means to feed said heel through said machine after 45 said rotative movement.

2. In a machine of the kind described, heel trimming means, means to feed a heel to said trimming means and to maintain said heel against said trimming means, means to grip said heel for a predetermined interval, and means to rotate said heel about a center while so gripped with its edge in trimming relation with the trimming means. 50

3. In a machine of the kind described, heel trimming means, heel feeding means, a pivoted carriage in the path of feed of said heel adapted to guide said heel about a center during trimming thereof, and means on said carriage adapted to grip said heel for a predetermined interval 60 during rotation of said carriage.

4. In a machine of the kind described, heel trimming means, heel feeding means, a pivoted carriage in the path of feed of said heel adapted to guide said heel about a center during trimming thereof, and cam actuated means on said carriage to grip said heel for a predetermined interval 65 during rotation of said carriage.

5. In a machine of the kind described, heel trimming means, heel feeding means, a pivoted carriage in the path of feed of said heel adapted to guide said heel about a center during trimming thereof, means on said carriage automatically actuated to grip said heel for a predetermined 70 interval during rotation of said carriage, and 75

resilient means to release said gripping means from said heel.

5 6. In a machine of the kind described, heel trimming means, heel feeding means, a pivoted carriage in the path of feed of said heel adapted to be engaged and rotated by said heel and to guide said heel about a center during trimming thereof, cam actuated means on said carriage to grip said heel for a predetermined interval during rotation of said carriage, and means to automatically release said gripping means from said heel.

10 7. In a machine of the kind described, heel trimming means, heel feeding means, a pivoted carriage in the path of feed of said heel adapted to be engaged and rotated by said heel and to guide said heel about a center during trimming thereof, means on said carriage adapted to grip said heel for a predetermined interval during rotation of said carriage, and means to discharge said heel from said machine.

15 8. In a machine of the kind described, heel trimming means, heel feeding means, a pivoted carriage in the path of feed of said heel adapted to be engaged and rotated by said heel and to guide said heel about a center during a trimming thereof, means on said carriage adapted to grip said heel for a predetermined interval during rotation of said carriage, means to discharge said heel from said machine, and means operable by said heel to return said carriage to initial position.

20 9. In a machine of the kind described, heel trimming means, heel feeding means, a pivoted carriage in the path of feed of said heel adapted to be engaged and rotated by said heel and to guide said heel about a center during trimming thereof, means on said carriage automatically actuated to grip said heel for a predetermined interval during rotation of said carriage, and resilient means to automatically release said gripping means from said heel.

25 10. In a machine of the kind described, heel trimming means, heel feeding means, a pivotally mounted carriage in the path of feed of said heel adapted to be engaged and rotated by said heel and to guide said heel about a center during trimming thereof, and manually operable means to adjust said carriage to vary the normal minimum distance between said center and said trimming means.

30 11. In a machine of the kind described, heel trimming means, heel feeding means, and a pivotally mounted carriage in the path of feed of said heel adapted to be engaged and rotated by said heel and to guide said heel about a center during trimming thereof, said carriage being automatically adjustable relative to said trimming means to compensate for irregularities in heel curvature.

35 12. In a machine of the kind described, heel trimming means, heel feeding means, a pivotally mounted carriage in the path of feed of said heel adapted to be engaged and rotated by said heel and to guide said heel about a center during trimming thereof, said carriage being automatically adjustable relative to said trimming means to compensate for irregularities in heel curvature, and manually operable means to adjust said carriage to vary the normal minimum distance between said center and said trimming means.

40 13. In a machine of the kind described, heel trimming means, heel feeding means, a pivotally mounted carriage in the path of feed of said heel adapted to be engaged and rotated by said heel and to guide said heel about a center during trim-

ming thereof, said carriage being automatically adjustable relative to said trimming means to compensate for irregularities in heel curvature, and means on said carriage adapted to grip said heel for a predetermined interval during rotation of said carriage. 5

10 14. In a machine of the kind described, heel trimming means, heel feeding means, a pivotally mounted carriage in the path of feed of said heel adapted to be engaged and rotated by said heel and to guide said heel about a center during trimming thereof, said carriage being automatically adjustable relative to said trimming means to compensate for irregularities in heel curvature, and cam actuated means on said carriage to grip said heel for a predetermined interval during rotation of said carriage. 15

20 15. In a machine of the kind described, heel trimming means, heel feeding means, a pivotally mounted carriage in the path of feed of said heel adapted to be engaged and rotated by said heel and to guide said heel about a center during trimming thereof, said carriage being automatically adjustable relative to said trimming means to compensate for irregularities in heel curvature, 25 means on said carriage automatically actuated to grip said heel for a predetermined interval during rotation of said carriage, and resilient means to release said gripping means from said heel. 30

25 16. In a machine of the kind described, heel trimming means, heel feeding means, a pivotally mounted carriage in the path of feed of said heel adapted to be engaged and rotated by said heel and to guide said heel about a center during trimming thereof, said carriage being automatically adjustable relative to said trimming means to compensate for irregularities in heel curvature, 35 cam actuated means on said carriage to grip said heel for a predetermined interval during rotation 40 of said carriage, and resilient means to automatically release said gripping means from said heel. 45

35 17. In a machine of the kind described, heel trimming means, heel feeding means, a pivotally mounted carriage in the path of feed of said heel adapted to be engaged and rotated by said heel and to guide said heel about a center during trimming thereof, said carriage being automatically adjustable relative to said trimming means to compensate for irregularities in heel curvature, 50 and cam operated means on said carriage adapted to grip said heel for a predetermined interval during rotation of said carriage. 55

45 18. In a machine of the kind described, heel trimming means, heel feeding means, a pivotally mounted carriage in the path of feed of said heel adapted to be engaged and rotated by said heel and to guide said heel about a center during trimming thereof, said carriage being automatically adjustable relative to said trimming means to compensate for irregularities in heel curvature, 60 cam operated means on said carriage adapted to grip said heel for a predetermined interval during rotation of said carriage, and cam controlled resilient means to automatically release said gripping means from said heel. 65

50 19. In a machine of the kind described, heel trimming means, heel feeding means, a pivotally mounted carriage in the path of feed of said heel adapted to be engaged and rotated by said heel and to guide said heel about a center during trimming thereof, and cooperating means on a fixed portion of said machine and on said carriage to present the untrimmed portion of said 70 75

heel to said trimming means during predetermined portions of the feeding operation.

20. In a machine of the kind described, heel trimming means, heel feeding means, a pivotally mounted carriage in the path of feed of said heel adapted to be engaged and rotated by said heel and to guide said heel about a center during trimming thereof, means on a fixed portion of said machine, and automatically adjustable means on said carriage cooperating with said last named means to present the untrimmed portion of said heel to said trimming means during the feeding operation.

21. In a machine of the kind described, heel trimming means, heel feeding means, a pivotally mounted carriage in the path of feed of said heel adapted to be engaged and rotated by said heel and to guide said heel about a center during trimming thereof, means on a fixed portion of said machine, automatically adjustable means on said carriage cooperating with said last named means to present the untrimmed portion of said heel to said trimming means during the feeding operation, and means to adjust the position of the means on the fixed portion of said machine relative to said trimming means.

22. In a machine of the kind described, heel trimming means, heel feeding means, a pivotally mounted carriage in the path of feed of said heel adapted to be engaged and rotated by said heel and to guide said heel about a center during trimming thereof, cooperating means on a fixed portion of said machine and on said carriage to present the untrimmed portion of said heel to said trimming means during predetermined portions of the feeding operation, and means to deflect the fins outwardly from said heel prior to presentation to the trimming means.

23. In a machine of the kind described, heel trimming means, heel feeding means, a pivotally mounted carriage in the path of feed of said heel adapted to be engaged and rotated by said heel and to guide said heel about a center during trimming thereof, and means on said carriage to grip said heel for a predetermined interval during rotation of said carriage, said carriage being automatically adjustable relative to said trimming means to compensate for irregularities in heel curvature, whereby the edge of the heel to be trimmed will be positively presented to the trimming means regardless of the contour of said heel.

24. In a machine of the kind described, heel trimming means, heel feeding means, a resiliently mounted pivoted carriage in the path of feed of said heel adapted to be engaged and rotated by said heel and to guide said heel about a center during trimming thereof, means on said carriage to grip said heel for a predetermined interval during rotation of said carriage, the resilient mounting of said carriage permitting automatic adjustment of said carriage relative to said trimming means to compensate for irregularities in heel curvature, whereby the edge of the heel to be trimmed will be constantly presented to the trimming means at substantially the same pressure regardless of the contour of said heel.

25. In a machine of the kind described, heel trimming means, means to feed a heel through said machine and past said trimming means in a substantially straight path, and means located in said path to grasp a heel after the trimming operation and discharge said heel from said machine.

26. In a machine of the kind described, heel trimming means, heel feeding means including a rotatable carriage in which said heel is held and rotated for a predetermined interval, means to grasp a heel after the trimming operation and discharge said heel from said machine, and means operable by said heel to return said carriage to normal position.

27. In a machine of the kind described, heel trimming means, heel feeding means including a rotatable carriage in which said heel is held and rotated for a predetermined interval, means to grasp a heel after the trimming operation and discharge said heel from said machine and means located in the path of said heel and engaged thereby during discharge thereof to automatically return said carriage to normal position.

28. In a machine of the kind described, heel feeding means, and cooperating heel trimming devices, a rockable shaft driving one of said devices, and resilient means tending to force said shaft and its trimming device toward the cooperating trimming device, whereby said trimming devices are automatically adjustable to accommodate varying heel thicknesses.

29. In a machine of the kind described, rotatable heel feeding means, and heel trimming means fixed thereto and rotatable therewith, one of said feeding means and its attached trimming means being resiliently mounted whereby said feeding means and said trimming means are automatically adjustable to accommodate varying heel thicknesses.

30. In a machine of the kind described, heel trimming means comprising a horizontally disposed lower rotary cutter consisting of a ring with a shearing edge, a horizontally disposed upper rotary cutter consisting of a disc with a shearing edge, and means to maintain said cutters in engagement.

31. In a machine of the kind described, heel trimming means comprising a horizontally disposed lower rotary cutter consisting of a ring with a shearing edge, a horizontally disposed upper rotary cutter consisting of a disc with a shearing edge, and resilient means to maintain said cutters in engagement.

32. In a machine of the kind described, heel feeding means, heel trimming means, a pivotally mounted carriage in the path of feed of said heel adapted to be engaged and rotated by said heel and to guide said heel about a center with its edge in trimming relation with said trimming means, resilient means bearing against said carriage whereby said carriage is automatically adjustable to vary the position of said center relative to said trimming means to compensate for irregularities in heel curvature, and manually operated means to disengage said resilient means from said carriage, whereby said carriage may be removed from said machine.

33. In a machine of the kind described, heel feeding means, heel trimming means, a pivotally mounted carriage in the path of feed of said heel adapted to be engaged and rotated by said heel and to guide said heel about a center with its edge in trimming relation with said trimming means, resilient means bearing against said carriage whereby said carriage is automatically adjustable to vary the position of said center relative to said trimming means to compensate for irregularities in heel curvature, manually operated means to disengage said resilient means from said carriage, whereby said carriage

may be removed from said machine, and means to maintain said resilient means in disengaged position.

34. In a machine of the kind described, a pair of annular horizontally disposed rotary cutters located in substantial engagement with each other, a horizontally disposed rotary cutter located on top of each of said first cutters, means to maintain said upper cutters in engagement 10 with said lower cutters, and means to adjust said lower cutters laterally with respect to said upper cutters.

35. In a machine of the kind described, a pair of annular horizontally disposed rotary cutters located in substantial engagement with each other, a horizontally disposed rotary cutter located on top of each of said first cutters, means to maintain said upper cutters in engagement with said lower cutters, the upper edges of said 20 lower cutters constituting a support for a heel, and the inner edges of said lower cutters flaring the fins from said heel before presentation to the cutting points.

36. In a machine of the kind described, a pair of annular horizontally disposed rotary cutters located in substantial engagement with each other, a horizontally disposed rotary cutter located on top of each of said first cutters, means to maintain said upper cutters in engagement 30 with said lower cutters, and means to adjust said lower cutters laterally with respect to said upper cutters, said upper cutters being automatically adjustable to accommodate varying heel thicknesses.

37. In a machine of the kind described, a pair of annular horizontally disposed rotary cutters located in substantial engagement with each other, a horizontally disposed rotary cutter located on top of each of said first cutters, means 40 to maintain said upper cutters in engagement with said lower cutters, and means to adjust said lower cutters as a unit laterally with respect to said upper cutters.

38. In a machine of the kind described, a pair of annular horizontally disposed rotary cutters located in substantial engagement with each other, a horizontally disposed rotary cutter located on top of each of said first cutters, means to maintain 50 said upper cutters in engagement with said lower cutters, means to adjust said lower cutters laterally with respect to said upper cutters, and a head on said machine constituting a support for said upper cutters, said head being tiltable relative to the lower cutters to permit access to said upper cutters.

39. In a machine of the kind described, a cylin-

drical member having an internal cutting edge, a cooperating shearing member, means to retain said shearing member in engagement with the end of said cylinder, whereby said internal cutting edge and said shearing member cooperate to form a cutting station, means to feed a heel with the finned edge thereof presented to said cutting station, and means to maintain said heel against said station at a constant pressure during 10 the cutting operation.

40. In a machine of the kind described, a cylindrical member having an internal cutting edge, a cooperating shearing member, means to retain said shearing member in engagement with the end of said cylinder, whereby said internal cutting edge and said shearing member cooperate to form a cutting station, means to feed a heel with the finned edge thereof presented to said cutting station, means to maintain said heel against said station at a constant pressure during 20 the cutting operation, and means to discharge the heel from the machine after completion of the cutting operation.

41. In a machine of the kind described, a plurality of independent heel trimming means 25 adapted to simultaneously operate on opposite sides of a heel, each means comprising a pair of cooperating cutters, and means to adjust the cutters in each pair relative to and independently of each other.

42. In a machine of the kind described, heel trimming means comprising a horizontally disposed lower cylindrical member having an internal cutting edge, a horizontally disposed upper shearing member cooperating with said cutting edge, and means to maintain said shearing member in engagement with the end of said cylinder.

43. In a machine of the kind described, heel trimming means comprising a horizontally disposed lower cylindrical member having an internal cutting edge, a horizontally disposed upper shearing member cooperating with said cutting edge, means to maintain said shearing member in engagement with the end of said cylinder, and means to adjust said shearing member 40 along said cutting edge.

44. In a machine of the kind described, heel trimming means, means to feed a heel to said trimming means, means to maintain said heel against said trimming means, means to grip said heel for a predetermined interval, means to rotate said heel about a center with its edge in trimming relation with the trimming means, and means to maintain said heel against said trimming means at a constant pressure.

EDWARD B. CARTER.
